(57) **CLAIM**

What is claimed is the ornamental design for set of contact sensors for doors and windows, as shown and described.

DESCRIPTION

FIG. 1 is a front perspective view of a set of contact sensors for doors and windows, showing our new design.

FIG. 2 is a front perspective view of the sensor body of FIG. 1.

FIG. 3 is a front view of the sensor body of FIG. 1.

FIG. 4 is a left side view of the sensor body of FIG. 1, the right side view being a mirror image of the left side view.

FIG. 5 is a rear view of the sensor body of FIG. 1.

FIG. 6 is a top view of the sensor body of FIG. 1.

FIG. 7 is a bottom view of the sensor body of FIG. 1.

FIG. 8 is a front perspective view of the magnet body of FIG. 1.

FIG. 9 is a front view of the magnet body of FIG. 1.

FIG. 10 is a right side view of the magnet body of FIG. 1, the left side view being a mirror image of the right side view.

FIG. 11 is a top view of the magnet body of FIG. 1, the bottom view being a mirror image of the top view; and, FIG. 12 is a rear view of the magnet body of FIG. 1.

The broken lines depict unclaimed environmental subject matter.
